(57) **CLAIM**

The ornamental design for a needle threader as shown and described.

DESCRIPTION

FIG. 1 is a top, front and right side perspective view of a needle threader showing the claimed design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view showing the needle threader in a closed state thereof.

The broken lines depict portions of the needle threader that form no part of the claimed design.

1 Claim, 9 Drawing Sheets
